UNITED STATES PATENT OFFICE.

JAMES JOLLY, OF BOLTON, ENGLAND, ASSIGNOR TO WHITIN MACHINE WORKS, OF WHITINSVILLE, MASSACHUSETTS, A CORPORATION OF MASSACHUSETTS.

COTTON COMBER.

Application filed January 16, 1923. Serial No. 612,929.

To all whom it may concern:

Be it known that I, JAMES JOLLY, a subject of the King of Great Britain, residing in Bolton, Lancashire, England, have invented the following described Improvements in Cotton Combers.

This invention relates to Heilman type combing machines, more especially to so-called double combers, and certain features 10 of the invention are capable of use with advantage in single combers as will appear below. The objects include general improvements in the organization and operation of the drive-head mechanism adapting the 15 same to be readily assembled and easily kept in repair, and also the provision of means whereby the operator may optionally operate the comber heads on one or both sides of a double comber as desired and may stop 20 those on one side without stopping those on the other, and also the organization with such control means and other parts of a scavenging system for removing the combed waste, which system is so related to the other 25 drive-head parts that it may be started in operation in advance of the comber heads, and whereby either side of a double comber may be stopped without affecting the removal of waste from the other side. These 30 and other objects which will hereinafter appear are accomplished in the form of double comber now preferred and taken for illustration in the accompanying drawings and it will hereinafter appear that the principles 35 incorporated in the illustrated machine may be easily incorporated in other, and widely different forms of combers.

In the accompanying drawings:—

Fig. 1, is an end elevation with parts 40 broken away of the drive-head end of the said comber;

Fig. 2, is a vertical transverse section on a plane indicated by line II—II of Fig. 3 but illustrating one of the comber heads in 45 vertical section;

Fig. 3, is a top plan of the drive-head end of the machine with certain parts broken away, or shown in section;

Fig. 4, is a large scale detail, partly in 50 axial section, of one of the two main gear wheels and the operator's control mechanism;

Fig. 5, is a detail plan of a part of the latter mechanism as will be later described;

Fig. 6, is a larger scale plan of one 55 comber-head, parts being broken away and shown in section, and

Fig. 7, is a rear or inside elevation of the 60 nipper frame removed from its normal support.

The figures above referred to show as much of the complete comber as will be necessary for those skilled in this art to make and use the invention and thoroughly understand its principles. For brevity's sake 65 they do not illustrate more than the drive head proper and the essential parts of the next adjacent comber head, but it will be understood that the complete machine comprises the drive-head, and a plurality of 70 comber heads all of identical design and all actuated by the drive-head mechanism, and that it is supplied with an appropriate delivery mechanism, at the end opposite the drive-head, as usual. The comber heads are 75 disposed in parallel rows on opposite sides of the central longitudinal plane of a common framework and faced in opposite directions. Referring to the drawings, the framework of the comber comprises a series 80 of usual leg sections appropriately united by and supporting a table girder 1 which forms the support for a series of upstanding frame sections. The terminal frame section at the drive-head end, is marked 2 and the next adjacent upstanding or intermediate section is marked 3, it being understood that there are some six or more sections, identical with section 3, distributed along the length of the girder 1, as usual, and according to the number of comber heads. The space between the 85 terminal frame section 2 and the next adjacent section 3 contains most of the mechanism constituting the drive-head, and the spaces between every two of the intermediate uprights 3 contain the elements constituting the comber heads. In a double comber each such space accommodates two comber heads which, as stated, face in opposite directions so as to form two opposed and parallel rows of comber heads, one on each side of the machine. Each of these rows of comber heads is associated with a sliver table 4 extending the length of the machine. The combed slivers are delivered by the 90 comber heads on each side onto these tables and are passed along them, by usual means to the draw box and delivery mechanism 100.

(not shown) at the opposite end. All this general arrangement is common in the art and needs no detailed illustration or description so far as the present invention is concerned. The comber heads may be identical in design and function, and their principal elements are actuated by longitudinal shafts which are journaled on the intermediate frame sections and extend into the drive-head space where they are provided with gears, the latter being organized in suitable gear trains and appropriately driven so as to actuate all the elements of the comber heads of both sides or rows. Each side of the double comber is provided with its own set of these shafts and gears, similarly and symmetrically arranged in the machine frame as will be observed in the drawing and later explained.

20 The general organization being as above briefly outlined and being, in fact quite the same as heretofore proposed for double combers, I proceed to the description of one of the comber heads, it being understood that all the comber heads are identical in construction. The roll of cotton lap to be combed, shown by dotted circle in Fig. 2, is placed upon the two creel rollers 5 and the lap is delivered therefrom to the swinging nipper frame 6, wherein it passes beneath the feed roll 7 and into the nipper jaws 8, by which its projecting end is held in the path of the half-lap needles on the revolving comb cylinder 9. After such projecting end has been combed by the cylinder the nipper frame swings forwardly and lays the combed tuft upon the rear end of the last preceding combed tuft which still remains held in the bite of the rear pair of detaching rollers 10, whereupon said rollers rotate forwardly as the nipper frame swings backwardly, thus detaching the combed tuft from the lap and at the same time overlapping it or piecing it with the previously combed material. In passing to the rollers, the tail of the tuft is drawn through the depending teeth of a top comb 11. From the detaching rollers 10, the material or fleece passes into the sliver pan 12 and thence through the trumpet and condenser rolls, 58 on to the sliver table 4. The nipper frame 6 swings on trunnions 6^a forming a horizontal axis and is moved back and forth by means of a connecting rod 13 and a crank on a longitudinal rock shaft 14. All of the several parts carried by the swinging frame, including the top comb 11, are operated by the effect of such swinging movement, according to the principles disclosed in my prior application Patent No. 1,446,750 dated February 27, 1923, to which reference may be had for further details of this type of combing head. The present construction differs from the prior application however, 65 in respect to the means whereby the swing-

ing of the frame operates to raise the upper nipper jaw knife 8, when the frame swings forward toward the detaching rolls. According to the present invention, the rear upturned arms 15 of the nipper knife are 70 pivotally connected to one of the members 16^a of a knuckle joint 16, the other member of which, 17, is pivotally attached to a part fixed on the machine frame. When the nipper frame is swung forward, by the operation of the rock shaft 14, as above described, the hinging of the knuckle joint 16 permits the initial forward movement to occur without operation of the nipper knife. When the abutments of the knuckle joint 75 come together, the restraint thus exercised on the nipper knife arms causes the latter to be rocked on their axes as the nipper-frame continues its forward movement, thereby opening the nippers. One of the 80 abutment members of the knuckle joint is provided with an abutment screw, shown in the member 16^a, which makes the joint adjustable, as will be obvious, to control the time of nipper opening. This adjustment is 85 more easily made and the operation is quieter than the cam roller means for the same purpose disclosed in said application. Otherwise the construction and operation of the 90 nipper frame parts are the same as fully disclosed in said application. In Figs. 6 and 7 the levers 7^a are the holding arms for the lap feed roller 7, these being under the pull of the springs 7^b. The arms 11^a are the arms of the top comb 11. The nipper knife 8 is carried by the pair of front arms 8^a secured to the cross rods 8^b which are journaled in the side walls of the nipper frame. The rear nipper knife arms 15 are set-screwed to these cross-rods 8^b inside the 95 frame. The springs 15^a urge the said arms upwardly and hence press the nipper knife 8 against the cushion plate. On account of the small scale of Fig. 2, many of these 100 parts are omitted or shown without reference numerals. The nipper frame is hung by its gudgeons 6^a on the framing so that it can be bodily removed when desired.

Each rock shaft 14, operates all the 105 comber heads of one row and each is extended into the drive-head, where it carries fast thereon a forked quadrant arm 18, the fork members of which carry adjustable 110 abutment screws engaging opposite sides of a cam lever 19. This lever 19 is loosely 115 mounted on shaft 14 and carries a cam roller engaged in the groove of a face cam 20, secured to or forming part of gear wheel 21, and by means of which the shaft 14 is 120 rocked through the appropriate angle. The 125 adjustment of the screws in the quadrant arm 18 changes the angular position of the rock shaft with reference to the cam groove and thus varies the swing-path of the nipper mechanism. At a convenient point, each 130

rock shaft 14 is connected by crank and link mechanism 22 with a ratchet wheel 23 and associated gearing arranged for intermittently driving the creel rollers 5 to supply 5 the lap to that side of the comb. As will be observed in Figs. 1 and 2, this link mechanism is adjustable to vary the stroke of the pawl so that the creel rollers may be set to the correct amount of rotation 10 conforming to the advance of the lap by the feed roller 7 in the swinging nipper mechanism. The detail of the creel roller mechanism is not important and will be understood from the drawings. It will be apparent 15 that the oscillation of rock shaft 14, operates all the parts of the nipper mechanism and the creel.

Each of gear wheels 21, above referred to, is mounted fast on a shaft 24, which is the 20 comb cylinder shaft for the corresponding side of the machine, and these wheels are therefore the index gears. They are driven in the present case, each by a pinion 25 appropriately journaled between the two gears 25 and close to the longitudinal center of the comb. The detail of the mounting of both pinions 25 is shown in larger scale in Fig. 4, wherein it will be seen that the pinion is formed on one end of a sleeve 26, 20 which also carries a brush-operating gear 27, a clutch member 28 and a clutch collar 29. The sleeve 26 is adapted to slide on its supporting shaft 30, which is journaled at one end in the frame section 2, and at the other 35 upon an intermediate frame bracket 31, mounted on the table girder 1. Each shaft 30 is keyed to a main driving gear 32 and may rotate within and relatively to the sleeve 26. The gear 32 carries a clutch member 33 complementary 40 to the sleeve clutch member 28, so that endwise movement of the sleeve 26 on the shaft 30 will cause the said sleeve and its two gears 25 and 27 to be engaged to or released from the driving gear 32. The 45 endwise movement of the sleeve is effected by a clutch lever 34 having its fulcrum axis 35 supported on the fixed bracket 36 and its operating arm extended downwardly, where it is subject to the tension of a spring 37, 50 tending to close or engage the clutch members, and where it is also connected by a link 38 to a slide block 39. The slide block carries an upstanding roller 40 adapted for engagement by the cam face of a cross slide 55 41 and the latter is connected by link 42 to a bell crank 43 (Fig. 3). This bell crank is journaled on a vertical stud on the corresponding side of the girder 1 and its outer end is connected by pin and slot to the end 60 of a control rod 44 mounted to slide horizontally in suitable lugs 45, fixed on the underside of the adjacent sliver table 4. When the operator slides the rod 44 on one side or the other, in a direction toward the drive head, the corresponding clutch lever 34 is

thereby moved against the tension of the spring and disengages the clutch members 28 and 33, so as to disconnect the index gear 21 from the main drive gear 32 for that side; reverse movement causes the engagement of 70 the clutch in like manner under the influence of the spring 37. The cam contour of the slide 41 is designed so that when it has disengaged the clutch members they will remain disengaged and the clutch-closing 75 spring 35 will be held under tension, until the control rod 44 has been restored to its former position.

The two gears 32, being duplicates and 80 symmetrically mounted as stated, are connected together preferably by mutual engagement of their respective teeth, so that the rotation of one will rotate the other. As thus arranged, either one of the shafts 30 85 may serve as the power shaft. For this purpose the right-hand shaft, in the present case, is extended beyond its bearing in the terminal frame section 2, where it is supplied with the usual fast and loose pulleys and a belt shipper, as shown in Figs. 1 and 90 3, this being the point of application of power to the machine.

Instead of such pulleys the shafts could be directly driven by electric power.

The brush-operating gear 27, on each 95 sleeve 26, drives an idler 27^a which is journaled in a bracket on the girder 1, and drives the gear 46 on the longitudinal brush shaft 47, which shaft, on each side, carries the rotary scavenger brushes 48, which clean all 100 the comb cylinders 9 of one side of the machine.

Each comb shaft or index gear 21 meshes 105 on its outer side with a gear 49 on the cam shaft 50, by means of which the detaching and piecing rolls and the sliver table calender rolls are operated. The detaching and piecing motion, shown in the drawings, will be recognized as the well known Nas- 110 mith detaching motion and will not require description further than to point out that it comprises two cams 51 and 52 on shaft 50. The former oscillates a rack segment 53 meshing with a gear 54 on the clutch shaft 115 and the latter oscillates a clutch lever 55, which controls the clutch 56 on said shaft. The combined action of said cams results in imparting a certain forward movement to the clutch shaft in one direction followed by 120 a movement of less extent in the reverse direction. This intermittent forward and back motion is transmitted through the train of gears marked 57 to the front and rear detaching roll shafts 10, causing them to operate in proper relation to the swinging nipper mechanism to carry out the well known Heilman combing cycle. The cam shaft 50 drives the sliver table calender rolls 58 through the train of gearing marked 59. 125 The function of these rolls, as will be un- 130

derstood, is to draw the combed sliver from the trumpets and deliver them upon the sliver tables.

The same cam shaft 50 also imparts the reciprocating motion to the top detaching and piecing roll and its connection for this purpose is clearly illustrated in Fig. 2. At some convenient point along the length of the comber, the shaft 50 is provided with an eccentric 60, appropriately connected to rock the rock shaft 61. The latter shaft carries a number of crank arms 62, which are connected by links 63 to a lever 64 (dotted lines Fig. 2). The upper end of this lever supports a holder arm 65, which holds the gudgeon of the rearward detaching roll. It will be obvious that the effect of these link and lever connections, of which there are two for each head, is to cause said rearward top detaching roll to be rolled backward and forward on the lower detaching roll synchronously with the operation of the detaching motion, and for the purpose of facilitating the overlapping of the tuft. The rearward or inward ends of the holder levers 65 are connected by stirrup links 66 to levers 67 from each of which is hung a weight 68. These weights press the top detaching roll upon the lower roll as will be evident. The two weight levers 67 for each head are adapted to be swung upwardly by the inward movement of the hand-operated push rod 68, which will thus relieve the rolls of pressure, as will also be obvious. Inasmuch as the cam shafts 50 are both driven from the comb cylinder gears 21 and the latter are driven from the pinions 25, it is obvious that the operator's control member 44 on each side of the machine is effective for starting or stopping whenever desired, all the combing elements on the corresponding side of the comber without affecting or requiring the stoppage of the combing elements on the opposite side.

Both rows of comber heads, are served by a common scavenging system, which is operated independently thereof. For this purpose such scavenging mechanism is connected to the source of power at a point on the power side of the clutch mechanism, above referred to, so that it is in operation so long as power is applied to the machine and whether either or both sides of the comber are in operation. The scavenging system in its preferred form comprises a main, longitudinal, suction air trunk 70, supported on the intermediate frame sections 3 and provided with pairs of oppositely disposed suction nozzles 71, respectively extending from the trunk to points adjacent the rear or inward side of the scavenging brush 48 of each comber head and in position to draw away the waste that is taken up by the brush from the half lap needles of the comb cylinder. At one end,

or at some convenient point in its length, the suction trunk 70 is connected to the suction side of a fan blower 72 and the outlet of said blower delivers the waste laden air onto a perforated drum 73 by means of which the waste is collected from the air and delivered into a conduit 74, through which it passes to some appropriate place of deposit. The design of this waste-removing mechanism forms no part of the present invention, and is disclosed and claimed in a co-pending application, Patent No. 1,479,392, filed by James J. McGowan. Instead of the system herein illustrated, any other suction or pneumatic waste-removing system could be substituted with like effect. In the present case, however, the suction fan is mounted on the comber-frame and its rotor shaft 75 is extended through the end of the terminal frame section where it carries a pulley 76 (Fig. 3), belted to a drive pulley 77, which is fast to the power shaft or to the fast pulley, or hand wheel 78. It will be apparent that by this connection, the pneumatic scavenging system is in operation whenever and for as long as power is applied to the machine and regardless of whether one side or the other, or both sides of the machine are in operation. By the arrangement described moreover, the scavenging system is compelled to be put in operation in advance of starting the comber heads, because in the usual way of starting the comber, the belt slipper is first shifted to the fast pulley, which starts the scavenger system, and thereafter the control members 44 are successively operated, to put the two sides of the comber in action. It is desirable that this sequence be followed in order that there shall be a sufficient suction draft on each scavenger brush when it begins its operation, and thus avoid the possibility of stoppages.

While I have herein described substantially all of the mechanism shown in the drawings, it will be understood that much of the same has been referred to merely for the purpose of indicating the relation of the invention thereto and for the purpose of a full disclosure thereof, and that there is no limitation intended to the particular design of the machine shown, except as specified in the appended claims, and it is to be particularly noted that the principles of organization defined by said claims can be incorporated in various types of cotton combers, irrespective of the type or mode of operation of the combing and detaching mechanism.

I claim:

1. A double comber comprising oppositely disposed rows of comber heads and a drive-head including a power shaft, two gears driven by said shaft, means associated with each of said gears adapted respectively to be

- engaged thereto or released therefrom and respectively connected for driving one of said rows, and an operator's control member for each of said means situated adjacent the 5 row of comber heads driven thereby.
2. A double comber comprising a framework having two rows of comber heads mounted on opposite sides thereof, and a drive-head including a main power shaft, 20 two gears driven by said shaft, a clutch member adapted to be driven by each of said gears, means driven by each clutch member for actuating all of the elements of one of said rows of comber heads, and an operator's 25 control member for each clutch member situated adjacent to the comber heads driven thereby.
3. A double comber comprising a framework incorporating two rows of comber heads, each row having a comb cylinder shaft and a detaching-roll shaft serving all 30 of the heads thereof, and a drive-head comprising two independent gear-trains respectively connected for actuating the cylinder 35 and detaching-roll shafts of each row, an operator's control means located alongside of each row and connections whereby such means independently controls the operation of each of said gear-trains.
4. A double comber comprising a single framework incorporating two oppositely disposed rows of comber heads, each row comprising a comb cylinder shaft provided with an actuating gear at its end, two driving 40 gear-trains each including the gear on a comb-cylinder shaft and a control rod mounted parallel to each row and having connections for independently controlling the drive of the gear-train corresponding to 45 that row, whereby the comber heads on each side of the comber may be started and stopped independently of the other.
5. A double comber comprising in a single framework, a drive head and two oppositely 50 disposed rows of comber heads, the row on each side comprising a plurality of actuating shafts for driving the comber heads on that side, an actuating gear-train connected to the several shafts on each side, two main gear wheels connected together so that the rotation of one drives the other, a power shaft connected to one of said wheels and adapted to drive both of them and means for 55 optionally establishing a driving connection between said main gear wheels and one or both said gear-trains.
6. A double comber comprising in a single framework, a drive head and two oppositely disposed rows of comber heads, each comprising a plurality of longitudinal actuating 60 shafts, an actuating gear-train for the shafts on each side, two main gear wheels symmetrically mounted in the machine frame, one in each side of the drive-head and connected together so that the rotation of one drives 65 the other, a power shaft connected to one of said wheels for driving both of them and means for optionally establishing a driving connection between each of said main gear wheels and one of said gear-trains. 70
7. A double comber comprising rows of comber heads, waste-removing means common to said rows, means for independently driving the comber heads of each row, and means independent of said driving means 75 for driving said waste-removing means.
8. A double comber comprising opposed rows of comber heads, a pneumatic waste-removing system common to both rows, means for independently driving and controlling 80 the comber heads on opposite sides and independent means for operating said waste-removing system, whereby either row of comber heads may be stopped without affecting the waste removal from the other 85 row.
9. In a comber, a comber head, a pneumatic waste-removing system therefor, and a drive-head including a power shaft, a clutching device, a gear set whereby said 90 clutching device transmits power to the elements of said comber head and driving connections between said power shaft and said waste-removing system independent of control by said clutching device. 95
10. A double comber comprising in a single framework, opposite rows of comber heads, each comprising a comb cylinder shaft with comb cylinders thereon for each head, a drive head including a power shaft and control means whereby said shaft may be 100 optionally caused to drive either or both of said cylinder shafts and a suction scavenger system common to both rows and driven by said power shaft independently of said control means. 105
11. A double comber comprising, in a frame, opposite rows of comber heads each comprising a comb cylinder, waste-removing means comprising a central air trunk with 110 opposite air nozzles extending toward and adapted to scavenge comb cylinders on opposite sides of the frame, gearing for operating the comber heads on both sides, and means independent of the operation of said 115 gearing for driving said waste-removing means.
12. A double comber comprising a drive-head including a power shaft and two opposite rows of comber heads all mounted in a single framework, each comber head comprising a comb cylinder and scavenger brush, a central suction air trunk supported in said framework in the space between said brushes, suction conduits extending from opposite sides of said trunk to said brushes, a suction fan having a fan shaft and a bearing for said shaft supported in said framework and a driving means between said shaft and the power shaft. 120
13. A double comber comprising a drive-head including a power shaft and two opposite rows of comber heads all mounted in a single framework, each comber head comprising a comb cylinder and scavenger brush, a central suction air trunk supported in said framework in the space between said brushes, suction conduits extending from opposite sides of said trunk to said brushes, a suction fan having a fan shaft and a bearing for said shaft supported in said framework and a driving means between said shaft and the power shaft. 125
14. A double comber comprising a drive-head including a power shaft and two opposite rows of comber heads all mounted in a single framework, each comber head comprising a comb cylinder and scavenger brush, a central suction air trunk supported in said framework in the space between said brushes, suction conduits extending from opposite sides of said trunk to said brushes, a suction fan having a fan shaft and a bearing for said shaft supported in said framework and a driving means between said shaft and the power shaft. 130

13. A double comber comprising in a single framework, two independent rows of comber heads, a pneumatic waste-removing system having a suction trunk located between and common to both rows, a suction fan mounted on the framework below said trunk, means for controlling the drive of each row of comber heads independently of said fan.
- 10 14. In a comber, a frame, a plurality of rows of comber heads, a suction waste-removing system therefor, comprising a longitudinal suction air trunk mounted in said frame, a suction fan mounted in said frame beneath said heads, a drive-head including a power shaft, gear-trains whereby said power shaft drives said rows of comber heads, and said fan and means for stopping either row independently of the other and the fan.
- 15 15. A double comber comprising a framework having mounted therein two independent rows of comber heads each comprising a comb cylinder shaft and each shaft having a gear, driving pinions for said gears located respectively in the space between them and means for optionally applying power to each or both of said pinions.
- 20 16. A double comber comprising a framework, two opposite rows of comber heads therein, each head comprising an upper support and a nipper frame hung thereon, a rock shaft connected to the nipper frames on each side and adapted to swing the same, a comb-cylinder shaft for each row, a gear on each comb-cylinder shaft, a common source of power for driving both said gears, a cam on each comb-cylinder shaft and independent means whereby said cams oscillate said rock shafts.
- 25 17. A double comber comprising a single framework incorporating two independent rows of comber heads, each head comprising a swinging nipper frame, comb cylinder and detaching rolls, an actuating rock shaft for the nipper frame of each row, a comb cylinder shaft, two driving gear sets for operating said shafts and means controlling each
- 30 gear set whereby either may be operated independently of the other.
- 35 18. A double comber comprising in a single framework, two rows of comber heads, each comprising a comb cylinder shaft with comb cylinders thereon for each head and nipper mechanism and detaching rolls, gear-trains on each side of the framework for driving said rows, one of said gear-trains having a connection to a source of power and the other train being driven from the first, and clutch mechanism appurtenant to each train.
- 40 19. A double comber comprising a single framework having mounted therein two independent rows of comber heads and a drive head including a main power shaft, two gears driven by said shaft, each having a clutch adapted to drive all the combing elements in each row including a rock shaft for each row, and creel mechanism for each row respectively driven by said rock shafts.
- 45 20. In a comber, the combination of lap feeding means, combing means and detaching rolls, including a top detaching roll and means for weighting the latter comprising a stirrup, a lever connected to the lower end thereof, a weight connected to said lever and stirrup and manual means for engaging said lever for relieving the stirrup of said weight.
- 50 21. In a comber, the combination with the comb cylinder and detaching rolls, of a nipper frame carrying feed mechanism and a nipper knife arm and adapted to swing toward and from said rolls, and a knuckle-joint connecting said arm to a relatively fixed part, said joint comprising abutment members limiting the angular movement of the joint-members, and adapted to cause the operation of the nipper knife at a predetermined point in the swinging movement of the frame.
- 55 22. In testimony whereof, I have signed this specification.
